DESIGN FOR A CHRISTMAS TREE
ORNAMENT

Charles R. Bickle, North Haven, Conn.

Application February 5, 1946, Serial No. 126,263

Term of patent 3½ years

(Cl. D29—1)

To all whom it may concern:

Be it known that I, Charles R. Bickle, a citizen of the United States, residing in the town of North Haven, county of New Haven, and State of Connecticut, have invented a new, original, and ornamental Design for a Christmas Tree Ornament, of which the following is a specification, reference being had to the accompanying drawings, forming a part thereof, in which

Figure 1 is a front elevational view of a Christmas tree ornament showing my new design; and

Figure 2 is a top plan view of the same.

I claim:

The ornamental design for a Christmas tree ornament, substantially as shown.

CHARLES R. BLICKLE.
